DESIGN FOR A TEXTILE FABRIC

Abe Tillman, New York, N. Y.

Application October 19, 1939, Serial No. 87,718

Term of patent 3½ years

To all whom it may concern:

Be it known that I, Abe Tillman, a citizen of the United States of America, residing in the city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design.

The design consists of a series of stripes separated by a row of stitches, each series embodying a plurality of stripes on a sheer background, as shown.

I claim:

The ornamental design for a textile fabric, substantially as shown and described.

ABE TILLMAN.
